(57) CLAIM

The ornamental design for posi-action beavertail grip safety,
as shown and described.

DESCRIPTION

FIG. 1 is a top rear perspective view of a posi-action
beavertail grip safety showing my new design;

FIG. 2 is right elevational view of FIG. 1;

FIG. 3 is a rear elevational view of FIG. 1;

FIG. 4 is a top elevational view of FIG. 1; and,

FIG. 5 is a bottom end view of FIG. 1.

The left side elevational view of FIG. 1 is a mirror image of
FIG. 2.

The phantom lines shown in FIGS. 1-5 do not form part of
the claimed design.
